UNITED STATES PATENT OFFICE.

ALBERT H. DE VOE, OF WESTFIELD, NEW JERSEY, ASSIGNOR TO THE SINGER MANUFACTURING COMPANY, OF ELIZABETH, NEW JERSEY, A CORPORATION OF NEW JERSEY.

FEEDING MECHANISM FOR SEWING MACHINES.

Application filed October 14, 1922. Serial No. 594,447.

To all whom it may concern:

Be it known that I, ALBERT H. DE VOE, a citizen of the United States, residing at Westfield, in the county of Union and State of New Jersey, have invented certain new and useful Improvements in Feeding Mechanisms for Sewing Machines, of which the following is a specification, reference being had therein to the accompanying drawings.

10 This invention relates to improvements in sewing machine feeding mechanisms, and while it is more particularly designed for embodiment in sewing machines fitted for stitching together the soles and uppers of Japanese tabis, certain features thereof are equally capable of being incorporated in sewing machines adapted for general use.

The invention has for one of its principal objects to increase the speed and efficiency 20 of sewing machines by the provision of improved supporting and actuating means for a four-motion upper feed-dog.

It has for a further object to provide improved means for actuating and controlling an auxiliary feeding mechanism to 25 produce different rates of advance of superposed plies of flexible cloth comprising the uppers of Japanese tabis relative to each other and to the sole to compensate for the different lengths of such fabric plies used in the alternate gradual and abrupt corrugations or bends of the material.

In its preferred form, the four-motion upper feed-dog is carried by a feed-bar so 35 connected with a vibratory feed-lift arm that the feed-dog is yieldingly pressed upon the work by a spring during the work-advancing movements thereof, but is positively lifted from the work and returned to initial 40 position without opposition by said spring, thereby relieving the operating mechanism from compressing the spring during approximately three-fourths of a complete movement of the feed-dog.

45 The clamping jaws comprising the auxiliary or differential feeding mechanism receive their work-advancing and return movements from a cam-actuated vibratory arm operating in opposition to a spring 50 which acts to return the clamping-jaws to an initial position. This initial position may be fixed by a predetermined adjustment of the degree of lost motion permitted between the vibratory arm and a clamping-

jaw carrier, and which position may be varying automatically through a complete operation by the action of a limit-determining cam receiving step-by-step advancing movements through a gear connection with a ratchet wheel. This ratchet wheel may 55 be rotated in opposite directions by either one of two reciprocated pawls selective at will, which pawls can both be maintained in ineffective positions in the constant retracted position of the jaws.

In the accompanying drawings, Fig. 1 is a front side elevation, partly in section, of a tabi-stitching machine embodying the present improvements. Fig. 2 is a rear side elevation, partly in section, of the same. Fig. 3 is a sectional view substantially on the line $x-x$, of Fig. 2. Fig. 4 is a sectional view substantially on the line $y-y$, of Fig. 2. Fig. 5 is a detail view of the yielding connection between the primary 70 feed-lift rock-shaft and the auxiliary feed pull-rod. Fig. 6 is a plan view of the bed-plate and auxiliary feeding device. Fig. 7 is an end elevation of the head of the bracket-arm, illustrating the primary feed-dog and its support. Fig. 8 is a perspective view of the abutment-cam actuating pawls.

The present invention comprises an improvement of the tabi-stitching machine illustrated in my Patent No. 1,191,068, of 75 July 11, 1916, to which reference may be had for an understanding of the general construction and operation of the parts not completely disclosed herein.

The frame comprises the bed-plate 1 and 80 hollow bracket-arm composed of the hollow standard 2 and overhanging tubular member 3, terminating at its forward end in the head 4 in which is journaled the reciprocating needle-bar 5 carrying the needle 6. 85 The needle 6 may cooperate with any suitable form of complementary stitch-forming mechanism and therefore no further reference is herein made thereto. The main-shaft 7, journaled in the bracket-arm member 3 90 carries the combined balance-wheel and belt-pulley 8.

The primary feeding-member comprises 95 a swinging feed-bar 9 to the lower end of which is secured by screws, as 10, the shank of a four-motion-upper feed-dog 11 divided centrally by the needle-aperture or notch 12 and provided with work-engaging spurs, as 100 105

13, spaced in the direction of feed. The feed-bar 9 has a yielding pin-and-slot connection with feed-lifting means constituting a yielding pivotal support for the feed-bar, and to this end the upper end of the feed-bar is bent to form a loop or hook 14 straddling a fulcrum and lifting pin 15, between spaced ears provided at the free end of a vibratory arm 16. The arm 16 is 5 fixed upon the forward end of a primary feed-lift rock-shaft 17, journaled in suitable lugs 18 provided on the rear side of the bracket-arm 3 and to which is clamped the split hub of a crank-arm 19 carrying a 10 roller-stud 20 which enters the cam-groove 21 formed in the rearward face of a cam 22 suitably secured upon the main-shaft 7. Interposed between a collar 23 adjustably secured upon the feed-bar 9 and a washer 24 15 bearing against the lift-arm 16 is a coiled spring 25 surrounding the feed-bar and urging the latter in the direction of the throat-plate 26 having the usual needle-aperture 27. That is, the tendency of the spring 25 is to 20 seat the upper end of the feed-bar upon the pin 15 and when so seated, the feed-bar and spring are lifted as a unit by the upward movements of the arm 16. These parts are adjusted so that the feed-dog 11 engages the 25 work before the arm 16 has completed its downward movement, thereby creating a clearance between the loop 14 and the pin 15 and leaving the feed-bar during its work-advancing movements solely under the pressure of the spring 25. Consequently the 30 initial upward movement of the arm 16 is aided by the spring 25 by reason of the feed-dog bearing upon the work and thereafter no force is consumed in further or again compressing the spring until the feed-dog again contacts with the work after its 35 return movement.

In order to impart work-advancing and return movements to the feed-dog, the feed-bar 9, which is rectangular in cross-section at its lower end, is slidingly guided by a similarly apertured block 28 provided with an elongated transverse slot 29 entered by a headed pin 30 secured by means of a set-screw 31 in the free end of a vibratory arm 32 depending from a feed-shaft 33. The rearward end of the slot 29 is normally maintained in contact with the pin 30 by a spring 34 carried by the arm 32 and bearing against the block 28. This construction permits of increasing the length of stitch being formed, when desired, by a pulling action upon the work rearward of the feed-dog. The feed-shaft 33 is suitably 40 journaled in the machine frame and has fixed to its rearward end a segment 35 provided with an arcuate slot 36 in which a slide-block 37, pivotally carried by one end of a link 38, is adjustably secured by means 45 of a clamp-lever 39. The opposite end of

the link 38 is pivotally connected, by pivot-bolt 40, with a triangular crank 41 having a hub 42 loosely journaled upon the primary feed-lift rock-shaft 17. Also carried by the crank 41 is a roller-stud 44 entering a cam-groove 45 in the forward face of the cam 22, which cam therefore also serves to impart the feeding and return movements to the primary feed-dog. 70

The auxiliary feed-clamp herein disclosed is constructed substantially in accordance with that illustrated in my prior patent before referred to and operates in the same manner for the same purpose. Improved actuating and controlling connections are however provided for this feed-clamp, which latter comprises a vibratory carrier-lever 46 having a tubular hub 47 mounted in a bearing boss 48 depending from the bed-plate 1. Journaled in the hub 47 is the depending fulcrum-pin 49 of the block 50 channeled in its lower face to receive the arm 51 provided with the lower work-clamping jaw 52. An upper clamping jaw 53 is formed upon the downwardly offset forward end of the arm 54 fulcrumed for edgewise movement upon the stud-screw 55 carried by the rocking support 56 which is in turn pivotally mounted upon the transverse pin 57 on the block 50. Interposed between the block 50 and the arm or lever 54 is the spring 58 which normally acts to separate the work-engaging jaws 52 and 53, a steady pin 59 fixed upon the lower jaw projecting through an aperture 60 in the upper jaw, thereby limiting the lateral movement of the upper jaw upon the fulcrum-stud 55. The width of the aperture 60 affords sufficient clearance for a slight lateral movement of the upper jaw relatively to the steady-pin 59. 90

Adjustably secured upon the rearward portion of the arm or lever 54, by means of screws 61 and 62, is the contact plate 63 having an extension 64 whose forward edge and lower face normally rest in contact with stop-shoulders provided upon a block 65 secured by screws 66 upon a pull-rod 67 journaled at its lower end for vertical movement in the bed-plate 1. The extension 64 is normally maintained in engagement with a stop-shoulder of the block 65 by means of a spring 68 interposed between a depending lip 69 of said plate 63 and the adjacent edge of the rocking support 56. 100

The pull-rod 67 is pivotally connected at its upper end with the arm 70 projecting forwardly from a sleeve 71, loosely journaled upon the feed-shaft 33 and provided with an upwardly extending crank-arm 72. The arm 72 carries a stud 73 embraced by a strap 74 at one end of the push-rod 75 which passes loosely through an eye formed in a rocking stud 76 carried by the crank-arm 77 fixed upon the feed-lift rock-shaft 17. A spring 78, stronger than the spring 58, 110

is interposed between the stud 76 and a nut 79 threaded upon the push-rod, said spring 78 serving to normally maintain the actuating parts in relatively fixed relationship, 5 whereby the rocking movements of the shaft 17 will not only impart lifting movements to the feed-dog 11, but will transmit its movements through the push-rod 75 to the pull-rod 67, whereby the auxiliary clamp is 10 alternately opened and closed by the downward movement of the block 65, permitting the spring 58 to open the jaws, and by the upward action of the block 65 upon the extension 64 to close the same. 15 The spring 78 is however adapted to yield when the primary feed-dog 11 is manually lifted and the clamp-jaws are opened for insertion and removal of the work. In order to effect this lifting action, a rocking sleeve 20 80 is loosely journaled upon the feed-shaft 33. Fixed to oscillate with this sleeve 80 is a hand-operated lever 81, projecting forwardly underneath the overhanging bracket-arm and under the action of a spring 82 which normally holds the forward end of 25 said lever 81 in raised position. The lever 81 is provided with a lateral extension 83 terminating in an apertured ear 84 journaled upon the outer end of the feed-shaft 33 projecting beyond the head 4, the additional 30 journaling affording a firmer bearing for said lever. The ear 84 carries a roller-stud 85 adapted to engage a cam-plate 86 secured by screws, as 87, upon the lift-plate 88, provided with guide-slots 89 and 90. The 35 guide-slot 89 coacts with a screw 91 threaded into the machine head and the slot 90 with the end of the feed-shaft for the purpose of confining the lift-plate 88 to vertical movements. The lower end of the lift-plate 40 carries a roller 92 adapted to engage a lug on a collar 93 secured by means of a screw 94 upon the feed-bar 9. It is evident that 45 upon manual depression of the forward end of the lever 81 against the action of the spring 82, the roller-stud 85 acts to lift the plate 88 and through the action of the roller 92, lift the feed-bar 9 and the feed-dog carried thereby. The return upward 50 movement of the lever 81 under the action of the spring 82 is limited by its contact with the overhanging bracket-arm. The feed-dog 11 reaches its upward limit of movement under the action of the lever 81 when the roller-stud 85 contacts with the 55 low-point 86' on the cam-plate 86. A further movement of the lever 81 is, however, permitted by the subsequent movement of the stud 85 beyond the low-point 86'. As 60 the stud 85 is now approaching the highest point in its orbit of movement, the feed-dog 11 is maintained in its raised position. The additional movement of the lever 81 serves to open the clamp-jaws of the auxiliary feed 65 in the following manner. The rocking sleeve 80 which oscillates with the lever 81 is provided at its rearward end with a shoulder 95 disposed in the path of movement of a rib 96 formed on the arm 70, which controls the opening and closing of the work-clamping jaws. In the normal operative position, sufficient clearance is provided between the shoulder 95 and the rib 96 to prevent coaction therebetween until after the feed-dog 11 has reached the described upper 70 limit of movement by depression of the hand-lever 81. Further movement of this lever serves to depress the pull-rod 67, thereby permitting the spring 58 to open the jaws, while in the return movement the block 65 75 acts upon the extension 64 to close the jaws. This movement of the arm 70 is permitted by the provision of the buffer-spring 78. From the foregoing it is apparent that during the operation of the machine the feed-dog 11 is raised and lowered simultaneously with the opening and closing of the work-clamping jaws 52 and 53, but that upon manual manipulation of the lever, said jaws 80 are opened after the feed-dog 11 is lifted and closed before said dog is lowered. 85 The block 50 is formed with the forwardly projecting arm 97 terminating in a segmental cam-edge 98 formed with the wedge-shaped notch 99 entered by the correspondingly shaped tooth 100 of a latch-bar 101 spring-pressed into latching relationship. Pivottally mounted upon the block 50 is the release lever 102 adapted to engage the latch-bar 101 for disengaging the tooth 100 from 90 the notch 99 to permit the auxiliary work-feeding members to be pivotally swung from operative position in which the jaws 52 and 53 are disposed in advance of the needle. 95 The block 50 is formed with the forwardly projecting arm 97 terminating in a segmental cam-edge 98 formed with the wedge-shaped notch 99 entered by the correspondingly shaped tooth 100 of a latch-bar 101 spring-pressed into latching relationship. Pivottally mounted upon the block 50 is the release lever 102 adapted to engage the latch-bar 101 for disengaging the tooth 100 from 100 the notch 99 to permit the auxiliary work-feeding members to be pivotally swung from operative position in which the jaws 52 and 53 are disposed in advance of the needle. 105 Projecting from the carrier-lever 46 is a hardened contact-pin 103 adapted to be engaged by a wear-block 104 fixed upon the free end of a depending arm 105, the hub of which is clamped by means of screws, as 106, upon a short shaft 107 suitably journaled in the machine-frame. Secured upon the shaft 107 is a crank-arm 108 carrying a roller-stud 109 entering a cam-groove 110 of a cam 111 fixed upon the main-shaft 7. The vibratory movements thus transmitted to the arm 105 by the cam 111 causes said wear-block 104 to engage the contact-pin 103 to 110 oscillate the clamping-jaws 52 and 53, while clamping the work therebetween, toward the primary feed-dog 11. The return movement of the jaws is effected by a spring 112, coiled about a stud 113 fixed upon the arm 105 and entering an aperture in the lever 46. 115 The effective action of said arm 105 is controlled by limiting the return movement of the lever 46, under the action of the spring 112, and thus creating lost motion between the arm 105 and said lever 46. This lost-motion may be constant to produce a prede- 120 125 130

terminated fulling or gathering action upon the upper, or it may vary automatically to produce a varying degree of fulling according to the adjustment of the parts about to be described.

The carrier-lever 46 is provided with an upstanding ear 114 into which are threaded two adjusting screws 115 and 116 adapted to be locked in adjusted positions by lock-nuts as 117. Loosely journaled upon a bearing stud 118 secured in an aperture in the standard 2 is a spur-gear 119 carrying a cam in fixed relation therewith. This cam has a concentric periphery 120 terminating in a cam-surface 121 projecting laterally beyond a flat web 122. The cam-surface 121 constitutes a variable abutment for the adjusting screw 115 to limit the return movement of the lever 46 and the web 122 comprises a constant abutment for the screw 116, it being understood that the screws 115 and 116 are so adjusted that one is ineffective in the operative position of the other. The spur-gear 119 meshes with a pinion 123 loosely journaled upon a stud-screw 124 threaded into the standard 2. Also loosely journaled upon the stud-screw 124 are a ratchet-wheel 125 and a manipulating knob 126, which are both pinned to the pinion 123 to rotate therewith. A spring 127 is interposed between the head of the stud-screw 124 and a flange 128 upon the knob 126 whereby the parts are maintained in operative relationship and whereby overthrow is prevented. By manipulating the knob 126, the pinion 123 may be rotated in either direction, which causes a corresponding rotation of the gear 119 to obtain an initial position of the cam-surface 121 with respect to the stop-screw 115 in the effective position of the latter. This initial position may be determined by means of an index finger 129 secured upon the bearing-stud 118 by means of a screw 130.

During the operation of the machine, the cam 121 may be rotated by means of either one of two pawls 131 and 132 pivotally supported upon fulcrum-screws, as 133, threaded into a carrier-block 134 secured upon the forward end of an oscillating member 135. The member 135 is provided with spaced apertured ears 136 loosely journaled upon the feed-shaft 33 on opposite sides of the hub of the segment 35, said member having an upwardly projecting arm 137 carrying a cam-roller 138 entering the feed-actuating cam-groove 45 at a point substantially diametrically opposite to the point of contact of the roller-stud 44 with said cam-groove.

The member 135 has a depending lug 139 carrying a guide-roller 140 tracking a guide-way 141 provided in the standard 2.

The pawls 131 and 132 have lateral extensions 142 and 143 each formed with a segmental depression, as 144, terminating in

stop shoulders, as 145. Positioned to coact with the depressions 144 is the periphery of a disk 146 provided with a segment-notch 147 adapted to alternately engage the stop-shoulders 145, while the extensions 142 and 143 are each yieldingly pressed upwardly by a spring 148 seated in apertured lugs 149 provided on the carrier-block 134. The disk 146 is carried by a spindle 150, journaled in a suitably apertured boss 151 on the carrier-block 134 and carrying a pawl-manipulating finger 152. In the central position of the finger 152, both of the pawl-extensions 142 and 143 are held depressed by the disk 146 against the action of the springs 148, but in either the right or left hand position of the finger 152, the disk 146 maintains one of the pawl-extensions depressed and permits the other to yield upwardly until the stop-shoulder engages a wall of the segment 85 notch 147. Consequently either one of the pawls 131 and 132 may be thrown into operative engagement with the ratchet-wheel 125, whereupon the oscillations of the member 135 are transmitted to the cam 121 to 90 rotate the latter in the desired direction.

When it is desired to effect a return movement of the clamping jaws 52 and 53 to a predetermined position throughout the operation of the machine the screw 115 is retracted out of engagement with the cam 121 and the screw 116 adjusted into the desired position of engagement with the web 122. To avoid unnecessary sliding wear upon the web 122, the finger 152 may be thrown into central or neutral position whereupon the cam 121 ceases to be rotated.

In the use of the machine as thus described, the primary feed-dog 11 and the upper clamping-jaw 53 are first successively lifted by manipulation of the lever 81, and the tabi-sole placed upon the throat-plate below the lower jaw 52 and the feeding-foot 11. The superposed plies of material 105 comprising the upper are then introduced between the jaws 52 and 53 and below the feed-dog 11, after which the previously lifted members are lowered into engagement with the work. When it is desired to automatically control the auxiliary feeding jaws 52 and 53 to progressively vary their fulling action, the stop-screw 115 is adjusted 115 the desired extent to engage the cam 121 and the stop-screw 116 released, while the finger 152 is thrown into either right or left hand position according to the nature of the operation.

The machine is now set in motion, whereupon the particular pawl in action imparts a step-by-step advancing movement to the cam 121 thereby constantly varying the retracted position of the auxiliary feeding jaws and consequently their amplitude of feeding movement. As the jaws 52 and 53 approach 120

the limit of each of their work-advancing movements, the upper jaw 53 is retarded by the extension 64 abutting against the shoul-
5 dered block 65, as in the machine of my prior Patent No. 1,191,068 and for the purpose of effecting a relative movement of the plies of fabric comprising the upper. The auxiliary feeding device forces the upper-fabric against the forward face of the primary feed-dog 11, in which condition it is secured to the sole by the descent of the needle. The feed-dog 11 and the upper clamp-jaw 53 are now mechanically lifted and returned to initial position, the spaced spurs 10 13 straddling the fulled portions of the fabric, whereupon the needle rises followed by work-advancing movements of the feeding devices.

Having thus set forth the nature of the invention, what I claim herein is:—

1. A four-motion-upper feeding mechanism for sewing machines comprising a feed-lift rock-arm fulcrumed upon the machine frame, means for actuating said arm, a feed-bar, a yielding pivotal support for said feed-bar upon said arm, a feed-dog on said feed-bar, means for imparting work-feeding movements to said feed-bar, and a spring interposed between said arm and said feed-bar and acting by its resilience throughout the work-feeding movements of said feed-dog to yieldingly maintain the feed-dog in engagement with the work.

2. A four-motion-upper feeding mechanism for sewing machines, comprising a feed-bar, a feed-dog carried thereby, a vibratory feed-lift arm, a pin-and-slot connection between said element and said arm, a spring interposed between said arm and said feed-bar, means for vibrating said arm, and operative connections for imparting work-advancing movements to said feed-dog including a connection yielding in the direction of feed.

3. A four-motion-upper feeding mechanism for sewing machines, comprising a feed-bar, a feed-dog carried thereby, a vibratory feed-lift arm, a pin-and-slot connection between said arm and said feed-bar permitting vertical movement of said feed-bar independently of said feed-lift-arm, a spring interposed between said arm and said feed-bar acting by its resilience throughout the work-feeding movements of said feed-dog to yieldingly maintain the feed-dog in engagement with the work, means for vibrating said arm, means for imparting work-advancing movements to said feed-dog, and manually operated means for lifting said feed-dog in opposition to said spring.

4. A four-motion-upper feeding mechanism for sewing machines, comprising a feed-dog, a spring yieldingly urging said feed-dog to engage the work, operative connections for imparting work-advancing

movements to said feed-dog, mechanically operated means unopposed by said spring for lifting said feed-dog above the work, and manually operated means for lifting said feed-dog in opposition to said spring. 70

5. A four-motion-upper feeding mechanism for sewing machines, comprising a feed-bar, a feed-dog carried thereby, vibratory feed and feed-lift elements, an operative connection between said feed-bar and the vibratory feed-element yielding in the direction of feed-movement of said feed-dog, and an operative connection between said feed-bar and the vibratory feed-lift element to permit relative yielding movements 75 therebetween in a direction substantially at right angles to the plane of the work.

6. The combination in a sewing machine including a bed-plate and an overhanging arm, of an upper feeding mechanism comprising a feed-bar, a feed-dog carried by said feed-bar, a feed-lift rock-shaft, means for actuating said rock-shaft, a vibratory arm carried by said rock-shaft, a yielding connection between the vibratory arm and said feed-bar, a spring opposing relative yielding movement between said arm and said bar in the work-engaging movement of said feed-dog, means for imparting feeding movements to said feed-bar, a manually manipulated lifter-lever fulcrumed upon said rock-shaft and extending forwardly underneath said overhanging arm, and an operative connection between said lever and said feed-bar to raise said feed-dog above the work in opposition to the action of said spring. 85 90 95

7. In a sewing machine, the combination with primary and secondary feeding members, and operative connections for imparting to said members differential work-advancing movements, of a feed-lift rock-shaft, a yielding connection between said rock-shaft and said primary work-feeding member, a yielding connection between said rock-shaft and the secondary work-feeding member whereby the latter is moved into and out of engagement with the work, a manually manipulated lifter-lever fulcrumed upon said rock-shaft, and differentially timed connections between said lifter-lever and the primary and secondary work-engaging members. 100 105 110 115 120

8. In a sewing machine, the combination with primary work-feeding mechanism comprising a feed-dog, and means for imparting operative movements thereto, of an auxiliary feeding device comprising a work-engaging member, a carrier therefor, means for imparting work-advancing movements to said member, yielding means for retracting said member to an initial position, a rotary cam having a variable and a constant abutment for determining said initial position, a plurality 125 130 of adjustable devices sustained by said car-

rier and selective at will for coaction with the variable and stationary abutments of said cam, and cam-rotating means.

9. In a sewing machine, the combination with primary work-feeding mechanism comprising a feed-dog, and means for imparting operative movements thereto, of an auxiliary feeding device comprising a work-engaging member, a carrier therefor, means for imparting work-advancing movements to said member, yielding means for retracting said member to an initial position, a rotary cam having a variable and a constant abutment for determining said initial position, a plurality of adjustable devices sustained by said carrier and selective at will for coaction with the variable and stationary abutments of said cam, cam-rotating means, and a throw-out device for rendering said cam-rotating means ineffective.

10. In a sewing machine, the combination with primary work-feeding mechanism comprising a feed-dog, and means for imparting operative movements thereto, of an auxiliary feeding device comprising a work-engaging member, a carrier therefor, means for imparting work-advancing movements to said carrier, yielding means for retracting said member to an initial position, a rotary cam comprising a variable abutment for said carrier to determine said initial position, and means for imparting step-by-step rotary movements to said cam including a ratchet-wheel, a plurality of reciprocating pawls, yielding means urging said pawls into operative engagement with said ratchet-wheel, means for reciprocating said pawls, and a pawl adjusting device for throwing both of said pawls into ineffective position.

40 11. In a sewing machine, the combination with primary work-feeding mechanism com-

prising a feed-dog, and means for imparting operative movements thereto, of an auxiliary feeding device comprising a work-engaging member, a carrier therefor, means for imparting work-advancing movements to said carrier, yielding means for retracting said member to an initial position, a rotary cam comprising a variable abutment for said carrier to determine said initial position, and means for imparting step-by-step rotary movements to said cam including a ratchet-wheel, a spring-pressed pawl provided with a stop-shoulder, a disk provided with a segment-notch positioned in the rotation of said disk to engage said stop-shoulder to maintain said pawl in operative engagement with said ratchet-wheel, manually manipulated means for rotating said disk to throw said pawl into ineffective position, and means for reciprocating said pawl.

12. In a sewing machine, the combination with primary work-feeding mechanism comprising a feed-dog, and means for imparting operative movements thereto, of an auxiliary feeding device comprising a work-engaging member, a carrier therefor, a vibratory lever positioned for engagement with said carrier to impart work-advancing movements to said member, means for vibrating said lever, yielding means for returning said carrier to initial position after the work-advancing movements thereof, a cam comprising a variable abutment for said carrier to effect an automatically varying degree of lost motion between said vibratory lever and said carrier to determine said initial position, and means for rotating said cam.

In testimony whereof, I have signed my name to this specification.

ALBERT H. DE VOE.
